UNITED STATES PATENT OFFICE.

HENRY A. REITZ, OF JOHNSTOWN, PENNSYLVANIA.

GAS-BURNER ATTACHMENT.

Application filed May 31, 1922. Serial No. 564,776.

To all whom it may concern:

Be it known that I, HENRY A. REITZ, a citizen of the United States, residing at Johnstown, in the county of Cambria and

5 State of Pennsylvania, have invented new and useful Improvements in Gas-Burner Attachments, of which the following is a specification.

This invention relates to attachments for 10 gas stoves and has for its object the provision of a novel device designed to be associated with the burners of a gas stove whereby to insure ample draft which will promote combustion and generate a greater 15 degree of heat with the consumption of less fuel so that the device will operate as a gas saver.

An important object is the provision of a 20 device of this character which is provided with adjusting means whereby the height of the outer drum member with respect to the burner may be regulated to insure the maximum benefit.

An additional object is the provision of 25 a device of this character which will be simple and inexpensive in manufacture, easy to install, efficient and durable in service and a general improvement in the art.

With the above and other objects and ad- 30 vantages in view the invention consists in the details of construction to be hereinafter more fully described and claimed and illustrated in the accompanying drawings in which:

35 Figure 1 is a plan view of the device mounted upon a gas burner,

Figure 2 is a cross sectional view there- through and

Figure 3 is a front elevation.

40 Referring more particularly to the drawings the letter A designates a gas burner of that type which has a central opening B, the letter C designates the feed pipe to the burner.

45 In carrying out my invention I provide an attachment which consists of a cylindrical outer drum 10 of a size to be slipped over the burner A and having at one point an opening 11 for the accommodation of 50 the feed element C. Located within this drum is a split spring ring 12 which engages upon the top of the burner A for regulating the position of the drum so that its upper edge may be located at any desired 55 height above the plane of the top of the burner. This split ring must have con-

siderable resilience, so that it will frictionally engage the drum sufficiently firmly to prevent the drum from slipping down on the burner.

60

The numeral 13 designates a flue member of cylindrical shape and open at both ends and having its lower end 14 reduced as shown for engagement within the opening B at the center of the burner. This flue member terminates considerably below the top of the drum as shown.

65

In the operation of the device it will be seen that the kettle or other receptacle containing matter to be cooked or heated is 70 placed upon the usual supporting structure of the stove and will be adequately supported thereby in the ordinary manner. When the gas issuing from the burner burns a draft will be created so that air will enter 75 the open bottom of the drum and the open bottom of the flue member 13. It will also be seen that outer currents of air are prevented from interfering with the action of the burner.

80

The flue member also operates to prevent burning at the center of the skillet or kettle in which cooking is being carried on as it tends to distribute the heat more uniformly.

85

From the foregoing description and a study of the drawings it will be apparent that I have thus provided a simply constructed and consequently inexpensive gas stove attachment which will work for economy as it operates to save gas while increasing the heating capacity of the burner. Owing to the simplicity of the construction it is apparent that the cost will be trivial and that there is nothing to get out of order.

90

While I have shown and described the preferred embodiment of the invention it is of course to be understood that I reserve the right to make such changes in the form, construction and arrangement of parts as will not depart from the spirit of the invention or the scope of the subjoined claims.

95

Having thus described my invention I claim:

1. In combination with a gas burner, a drum slidably engaged exteriorly upon the burner and open at its top and bottom, a retaining element within the drum engaging the top of the burner, and a central flue member open at both ends and detachably engaged within the opening at the center of the burner.

105

2. In combination with a gas burner hav-

110

ing a central opening, a cylindrical drum slidably engaged exteriorly upon the burner, said drum being formed with an opening for the accommodation of the gas feed pipe leading to the burner, and a flue detachably engaged within the central opening of the burner and terminating below the top of the drum.

3. In combination with a gas burner having a central opening, a cylindrical drum slidably engaged exteriorly upon the burner, said drum being formed with an open-

ing for the accommodation of the gas feed pipe leading to the burner, a flue detachably engaged within the central opening of the burner and terminating below the top of the drum, and a split spring ring adjustably positioned within the drum and engaging the top of the burner for varying the position of the top of the drum with respect to the top of the burner.

In testimony whereof I affix my signature.

HENRY A. REITZ,
